United States Patent Office

Des. 187,623
Patented Apr. 5, 1960

187,623

MARINE AIR CONDITIONER OR THE LIKE

Rayburn M. Hamilton, Houston, Tex.

Application October 8, 1958, Serial No. 52,904

Term of patent 14 years

(Cl. D62—4)

Fig. 1 is a top perspective view of a marine air conditioner embodying my new design;

Fig. 2 is a bottom perspective view thereof taken from the opposite side and end from the side shown in Fig. 1;

Fig. 3 is a top plan view of the air conditioner; and,

Fig. 4 is a side elevation thereof.

I claim:

The ornamental design for a marine air conditioner or the like, substantially as shown.
